SCRAPING DEVICE

Herbert C. Otis, Dallas, Tex.

Application May 16, 1938, Serial No. 208,323

11 Claims. (CL 166—18)

This invention relates to new and useful improvements in scraping devices.

One object of the invention is to provide an improved device which is particularly adapted for use in removing paraffin, or other accumulation from the wall of the bore of well tubing, or other pipe.

An important object of the invention is to provide an improved scraping device for removing paraffin from well tubing which is constructed so that the scraping members thereof are circumferentially retractile, whereby the outside diameter of the scraper formed by said members may be reduced to permit lowering of the device through a tubing bore having a coating of paraffin therein, without said members scraping or removing the paraffin during such lowering; the members being automatically expanded on the upstroke to remove the paraffin from the tubing bore.

A particular object of the invention is to provide an improved paraffin scraper having a plurality of arcuate scraping members which are arranged to be expanded to form a circumferential scraper, whereby removal of the coating or accumulation of paraffin on said wall may be accomplished.

Another object of the invention is to provide an improved scraping device including a support having arcuate scraping members mounted thereon, said members being constructed so as to coact with each other and the support, whereby the members are rigidly sustained in scraping position and the load imposed thereon is carried by the support, rather than by the members alone.

A further object of the invention is to provide an improved paraffin removing device including a tapered support having radially movable scraping elements mounted to slide vertically thereon, whereby when the blades move vertically with relation to the support they are expanded or retracted radially so as to vary the diameter of the scraper formed by the blades.

A still further object of the invention is to provide a scraping device of the character described which may be run into or removed from the well tubing on a wire line or cable; or which may be dropped into the tubing so as to fall by gravity and removed therefrom by fluid pressure.

A construction designed to carry out the invention will be hereinafter described, together with other features of the invention.

The invention will be more readily under-

stood from a reading of the following specification and by reference to the accompanying drawings, in which an example of the invention is shown, and wherein:

Figure 1 is a view, partly in elevation and partly in section, of an improved scraping device, constructed in accordance with the invention and showing the scraper members in a retracted position. 5

Figure 2 is a similar view with the scraping members expanded into scraping position.

Figure 3 is a view similar to Figure 2 and viewed at right angles to the latter.

Figure 4 is a horizontal, cross-sectional view taken on the line 4—4 of Figure 2. 15

Figure 5 is a horizontal, cross-sectional view taken on the line 5—5 of Figure 2.

Figure 6 is a horizontal, cross-sectional view taken on the line 6—6 of Figure 2.

Figure 7 is a horizontal, cross-sectional view taken on the line 7—7 of Figure 2. 20

Figure 8 is an isometric view of the scraper assembly.

Figure 9 is an isometric view of one-half of the sleeve or body which carries the scraper members, and showing the walls thereof in sections. 25

Figure 10 is an isometric view of two of the scraper members.

Figure 11 is a transverse, vertical, sectional view taken through the supporting sleeve or body. 30

Figure 12 is a transverse, vertical, sectional view taken on the line 12—12 of Figure 11.

Figure 13 is a horizontal, cross-sectional view taken on the line 13—13 of Figure 11. 35

Figure 14 is a transverse, vertical, sectional view of a modified form of the invention, with the scraping members in a retracted position.

Figure 15 is a view, partly in elevation and partly in section, of this form of the invention with the scraping members in an expanded or scraping position. 40

Figure 16 is a view similar to Figure 15 and showing the device viewed at a right angle with respect to Figure 15. 45

Figure 17 is a horizontal, cross-sectional view taken on the line 17—17 of Figure 15.

Figure 18 is a horizontal, cross-sectional view taken on the line 18—18 of Figure 15. 50

Figure 19 is a view, partly in elevation and partly in section, of another form of the invention, with the scraping members retracted.

Figure 20 is a similar view, with the scraping members expanded into scraping position. 55

Figure 21 is a horizontal, cross-sectional view taken on the line 21—21 of Figure 20.

Figure 22 is a view, partly in elevation and partly in section, of still another form of the invention,

Figure 23 is a horizontal, cross-sectional view taken on the line 23—23 of Figure 22, and

Figure 24 is a plan view of one of the scraping members shown in Figure 22.

10 In the drawings, the numeral 10 designates an elongate support, or mandrel, which has its upper portion substantially cylindrical in cross-section. Below the cylindrical portion, the outer surface of the mandrel is flared or inclined outwardly, as shown at 11, and an enlarged flange 12 is preferably made integral with the lower end of the mandrel. The provision of the collar forms an external, annular shoulder 13 at the base of the flared or inclined surface 11 of said mandrel. The lower end of the collar 12 may be bevelled at its outer peripheral edge to facilitate lowering of the mandrel through a well tubing A, or other tubular member.

The upper end of the mandrel 10 is externally 25 screw-threaded to receive a cap member, or head, 14 which has an external flange 15 at its upper end. The underside of the flange is recessed or undercut at 16, whereby a suitable tool (not shown) for raising or lowering the mandrel 30 through the tubing may be engaged therewith, as will be explained.

A scraper assembly B is slidably mounted on the mandrel 10, being confined between the head 14 and the collar 12. The assembly includes an 35 annular body or sleeve 17 which surrounds the mandrel and is slidable vertically thereon. A pair of upper scraper members 18 and a pair of lower scraper members 19 are carried by the body or sleeve and the members have their inner surfaces engaging the outer surface of the mandrel 10, whereby as the sleeve 17 and blades move downwardly of the mandrel, their lower ends are moved outwardly by the inclined surface 11 of said mandrel; upward movement of the sleeve 45 and members permits inward movement of said members to a retracted position (Figure 1).

For mounting the scraper members 18 and 19 in the sleeve or body 17, the bore 17' of said sleeve is formed with an internal, annular recess 50 20 which is located near the upper end of said bore (Figure 9). A pair of diametrically opposed vertical grooves or channels 21 are formed in the wall of the bore 17' and extend downwardly from the recess 20 to the lower end of the sleeve and 55 these grooves are adapted to receive the upper scraper members 18. The lower portion of the sleeve is reduced to form an annular skirt 22 and an arcuate notch 21', which has a width greater than the width of the grooves 21, is provided 60 in the skirt adjacent each groove.

Each upper scraper member comprises a T-shaped shank or arm which is formed with an arcuate cutting blade 18' at its lower end, preferably made integral therewith. The lateral 65 arms 18a of the shank are arranged to be inserted within the annular recess 20 and when so inserted, the scraper member is suspended from the shoulder 20' formed by the recess, with the shank 18 extending through the vertical channel 70 21 and the cutting blade 18' disposed within the notch 21' at the lower end of the sleeve 17. The transverse width of the blade is greater than the combined width of the shank and the wall of the sleeve 17, whereby the outer surface of the 75 blade projects beyond the outer surface of the

sleeve 17 when the shank is engaging the bottom of the groove or channel 21, as shown in Figure 2.

With the above arrangement, the upper scraper members 18 are suspended from the annular recess 20 and may undergo a limited lateral movement. Displacement of the members is prevented by the outer surface of the mandrel 10 which is adjacent the inner vertical surfaces of the shanks of the members. When the members 18 are in position within the sleeve, the bottom of each cutting blade 18' is substantially flush with the lower edge of the skirt 22.

The lower scraper members 19 are located between the lower members 18, whereby the four members are preferably equally spaced around the sleeve. The lower members are constructed in substantially the same manner as the upper members, except that the shank of each is elongated so as to position the cutting blades 19' below the lower end of the skirt 22 of the sleeve 11. The lower members 19 are suspended from the annular recess 20 in the same manner as the members 18, and the shank of each lower member extends through a vertical groove 24, 25 similar to the grooves 21. With such arrangement, the lower scraper members 19 are capable of a limited lateral movement so as to move radially of the sleeve 17.

The arcuate cutting blades 18' of the upper members 18, as well as the arcuate cutting blades 19' of the lower members 19, are of such length as to extend through an arc greater than ninety degrees, whereby the ends of said blades overlap each other (Figure 6). This overlapping is possible because the blades 19' are disposed in a horizontal plane below the blades 18' (Figures 1 to 3) and it is preferable that the upper surfaces of the lower blades 19' engage the underside of the overlapping ends of the upper blades 18', whereby a continuous circumferential scraper is formed by the blades.

In using the device, the same may be dropped into the well tubing A so as to fall therethrough by gravity; or a suitable tool (not shown) may be engaged beneath the flange 15 to permit lowering. Suitable guide ribs or projections 25 may be formed on the exterior of the sleeve or body 17 to prevent the cutting blades from hanging or catching on the tubing couplings or other irregularities and also to aid in guiding the same axially through the tubing during its travel therethrough. At the start of the lowering, the sleeve may be in the position, shown in Figure 2, but as soon as the blades or the guides strike a projection or accumulation on the wall of the tubing bore the frictional engagement of said blades or ribs with such projection will cause the sleeve to ride upwardly on the downwardly moving mandrel, whereby the sleeve, and scraper members 18 and 19 carried thereby, are moved to the position shown in Figure 1. In such position, the sleeve and members are opposite the cylindrical upper portion of the mandrel, and the lower ends of the members have moved inwardly, whereby the cutting blades 18' and 19' are in a retracted position and the outer diameter of the scraper formed by said blades is reduced to permit fast lowering of the device through the paraffin zone. The lower, outer edges of the blades 18' and 19' are rounded so as to obviate their hanging on the tubing couplings or other irregularities in the tubing A, as the device moves downwardly therethrough.

When the blades 18' and 19' are retracted, 75

their outer surfaces move radially inwardly, with the result that the outer diameter of the circumferential scraper formed by said blades is reduced. This assures that the blades can readily 5 move downwardly through the paraffined wall of the tubing without engaging the paraffin or performing any scraping at any point during lowering of the device. It is preferable that the members 18 and 19 can move a sufficient distance inwardly so that the outer surfaces of the blades 18' and 19' be substantially flush with the outer wall of the sleeve 17 when in a retracted position.

As is well known, paraffin usually accumulates near the upper portion of the well tubing and ordinarily, it is not necessary that the device be lowered to the bottom of the tubing, it being sufficient that it be lowered to a point below the paraffin zone. Any suitable means may be employed to stop downward movement of the device 20 and in the drawings, a transverse stop pin 26 is disclosed. The pin is located below the paraffin zone and extends transversely across the tubing bore; manifestly, when the collar 12 on the lower end of the mandrel strikes the pin, further downward movement of the mandrel is prevented.

As the mandrel strikes the pin 26 and movement thereof is halted, the weight of the sleeve 17 and the scraper members 18 and 19 thereon, cause the sleeve to slide downwardly on the mandrel into engagement with the shoulder 13. Such downward sliding of the mandrel causes the members 18 and 19 to be moved radially outwardly, due to the engagement of the inner surfaces of said members with the flared or inclined surface 31 of the mandrel. Thus, the scraping blades 18' and 19' are moved into an expanded or scraping position (Figures 2 and 3) and in such position the bottom of each lower blade 19' rests on the shoulder 13. It is noted in the event 40 that the sleeve 17 does not slide downwardly on the mandrel 10 by gravity, as explained, the device is moved upwardly and when the ribs strike a projection or irregularity on the tubing wall, said sleeve is forced downwardly on the 45 upwardly moving mandrel to expand the blades into scraping position.

The device may be raised to the surface either by the well pressure below the same or by a suitable tool (not shown) engaged with the shoulder 15 on the head 14. As the device moves upwardly, the expanded overlapping blades 18' and 19' form a circumferential scraper, which engages the accumulation on the wall of the tubing bore, whereby the bore is scraped clean 55 of the accumulation, such as paraffin. The load imposed on the blades, as they perform the scraping operation is transferred to the shoulder 13 of the mandrel since the lower blades 19' rest directly on said shoulder, and the upper blades over- 60 lie said lower blades at the ends thereof. With such arrangement, the mandrel rather than the scraping members 18 and 19 carries the load.

As the device travels upwardly through the tubing bore, the wall of said bore is cleaned by the 65 circumferential scraper formed by the scraper blades 18' and 19'. Since the outer expanded diameter of the blades 18' and 19' is less than the bore of the tubing, by-pass of fluid or pressure past said blades may occur. This well fluid flowing upwardly past the upwardly moving device 70 will tend to keep the upper surfaces of the blades clean by lifting the paraffin, or other accumulation which has been removed by the blades. The fluid will flow past the device 75 at a relatively high velocity, due to the restricted

annular passage and said fluid is thus directed against the accumulation, whereby it will tend to remove the paraffin by a cutting or washing action. The bore is thus efficiently cleaned upon the upward travel of the device. When worn, 5 the scraper members 18 and 19 may be readily replaced by merely removing the head 14 and the sleeve 17 from the mandrel 10.

In Figures 14 to 18, a modified form of the invention is shown. In this form, an elongate 10 mandrel 30 has the upper portion of its outer surface tapered or inclined at 30' to form an expanding surface. A plurality of vertical dovetail grooves 31 are provided in this inclined surface and extend from the upper end of the mandrel to a point spaced from the lower end thereof. A sleeve 32 surrounds the mandrel and is slidable vertically with relation thereto. A pair of upper arcuate scraper blades 33 are adapted to fit within arcuate recesses 34 in the outer surface 15 of the sleeve and each blade has an inwardly extending arm 35 (Figures 16 and 17) which passes through a radial opening 36 in the sleeve. The inner end of each arm 35 is dovetailed so as to slidably engage within one of the grooves 31 25 of the mandrel.

A pair of lower scraper blades 37 are similarly mounted in the sleeve below the blades 33 and in offset relation thereto. Manifestly, when the sleeve moves upwardly on the mandrel, the blades 30 33 and 37 are retracted, due to their inner ends riding within the inclined grooves 31 (Figure 14); similarly, downward movement of the sleeve on the mandrel causes outward movement of the blades into scraping position (Figures 15 and 16). 35 Displacement of the blade arms from the upper ends of the grooves 31 is prevented by a collar 38 which overhangs the grooves. The collar is made integral with a fishing neck 39 and a depending threaded pin 40 on said neck is arranged 40 to be screwed into an opening 41 in the upper end of the mandrel 30. The operation of this form is the same as the first form, the blades 33 and 37 being retracted during lowering and expanded during raising. Retraction and expansion of the blades varies the outside diameter 45 of the circumferential scraper formed by said blades, whereby the device may be readily lowered through the paraffin zone, and also whereby removal of the accumulation on the wall of the bore is accomplished when the blades are expanded and the device raised.

Another form of the invention is shown in Figures 19 to 21, wherein an elongate mandrel 45, similar to the mandrel 10, is provided. This 55 mandrel has an external, annular shoulder 46 at the base of the inclined expanding surface 11' and below said shoulder the mandrel is cylindrical. At the base of the cylindrical portion, an external flange 47 is provided. A sleeve 47, similar to the sleeve 17, is slidable on the mandrel and has the scraper members 18' and 19' mounted therein in a similar manner to the mounting of the members in the sleeve 17. However, the lower end of the sleeve 47 does not terminate adjacent 60 the blades 18' and 19' but extends therebelow to provide a depending skirt portion 48, which slides on the outer cylindrical portion of the mandrel, which portion is below the shoulder 46. The sleeve 47 has radial openings 49 through which 65 the blades 18' and 19' project and when the blades are retracted, their outer surfaces are substantially flush with the exterior of the sleeve (Figure 19). With the blades retracted, the lower edge of the skirt 48 of the sleeve 47 is just below the 70

shoulder 46, whereby as the device moves downwardly through the tubing, foreign matter cannot accumulate below the retracted blades. When the blades are expanded (Figure 20) the 5 lower blades 19' rest on the shoulder 46 and the lower end of the sleeve engages the flange 12' at the lower end of the mandrel. The upper blades 18' may be provided with depending lugs 18b which are arranged to engage the shoulder 46 10 when said blades are expanded and, in this manner, the load imposed on the blades 18' and 19' as they perform their scraping operation is transferred to the mandrel 45.

Still another form of the invention is illustrated in Figures 22 to 24, wherein a tapered mandrel 50 is provided. The mandrel has vertical grooves or channels 51 therein and a plurality of eccentric superimposed scraper rings 52 are slidably mounted on the mandrel. Each ring 20 has a scraping surface 53 which extends through an arc of more than ninety degrees and the surfaces 53 are offset radially around the mandrel to form a circumferential scraper. The rings are held in their proper relationship and are guided 25 in their vertical movement, by vertical keys or ribs 54, which are secured to the rings and which engage in the grooves 51. The rings are confined on the mandrel between an enlarged collar 55 on the lower end of said mandrel and a head 30 56 on the upper end thereof. A sleeve or collar 58, having guide ribs 59, rests on the uppermost ring 52 and its weight holds the rings in engagement with each other. When the rings move upwardly on the mandrel, their scraping portions 53 35 may be retracted radially inwardly and when said rings move downwardly on the mandrel, they are expanded into scraping position. The operation of this form, with regard to its use in the tubing, is the same as the forms previously described. 40

The foregoing description of the invention is explanatory thereof and various changes in the size, shape and materials, as well as in the details of the illustrated construction may be made, within the scope of the appended claims, without departing from the spirit of the invention. 45

What I claim and desire to secure by Letters Patent is:

1. A scraper including, a support, and circumferential scraping means independently and 50 loosely mounted on the support arranged to be freely expanded and retracted to vary the outer diameter thereof without breaking the circumferential continuity, said scraping means providing continuous circumferential cutting edges.
2. A scraping device including, a support having a projection thereon, and arcuate scraping members independently and loosely mounted on the support and freely movable radially thereof to an expanded or retracted position, said scraping members coacting with each other to provide 60 continuous circumferential cutting edges and also coacting with the projection on the support, whereby the members are rigidly sustained in an expanded position.
3. A scraping device including, an axial support having a stationary inclined portion on its outer surface, a plurality of scraper members having arcuate overlapping scraping faces loosely surrounding the support and forming a circumferential scraper, said members being freely slideable 70 longitudinally of the inclined portion of the support, whereby the scraping faces are retracted and expanded in a radial direction to vary the outside diameter of the circumferential scraper.
4. A scraping device including, an axial support 75

having a stationary inclined portion on its outer surface, a plurality of scraper members having arcuate overlapping scraping faces loosely surrounding the support and forming a circumferential scraper, said member being freely slideable 5 longitudinally of the inclined portion of the support, means for retaining the members in contact with the inclined portion of the support, whereby as the members are moved longitudinally on the support the scraping faces thereof are retracted or expanded in a radial direction. 10

5. A scraper including, an axial mandrel having an inclined portion on its outer surface, an annular sleeve surrounding the mandrel and movable thereon, and a plurality of scraper members 15 carried by the sleeve and having arcuate scraping faces, said members being arranged to engage and ride upon the inclined portion of the mandrel, whereby when the sleeve is moved on the mandrel, the scraping members are expanded or contracted. 20

6. A scraper including, an axial mandrel having an inclined portion on its outer surface, an annular sleeve surrounding the mandrel and movable thereon, and a plurality of scraper members 25 carried by the sleeve and having arcuate scraping faces, the scraper faces of adjacent members being located in different horizontal planes and being disposed in overlapping relation so as to form a circumferential scraper, said 30 members being arranged to engage and ride upon the inclined portion of the mandrel, whereby when the sleeve is moved on the mandrel, the scraping members are expanded or contracted. 35

7. A scraper including, an axial mandrel having an inclined portion on its outer surface, a sleeve surrounding the mandrel and movable longitudinally thereof, and a plurality of scraper members mounted within the bore of the sleeve and arranged to swing from their upper ends and having arcuate scraper faces arranged to be expanded so as to project beyond the outer surface of the sleeve and coacting with each other to form a circumferential scraper, the inner surfaces of the members engaging the inclined portion of the mandrel, whereby the members are expanded or retracted radially when the sleeve is moved longitudinally of the mandrel. 40

8. A scraper including, an axial mandrel having an inclined portion on its outer surface, a sleeve surrounding the mandrel and movable longitudinally thereof, and a plurality of scraper members mounted within the bore of the sleeve and arranged to swing from their upper ends and having arcuate scraper faces arranged to be expanded so as to project beyond the outer surface of the sleeve, the scraper faces of adjacent members being located in different horizontal planes and being disposed in overlapping relation so as to form a circumferential scraper, the inner surfaces of the members engaging the inclined portion of the mandrel, whereby the members are expanded or retracted radially when the sleeve is moved longitudinally of the mandrel. 50

9. A scraper for a tubular element including, a support, a scraper assembly on the support and having a plurality of overlapping radially movable scraper members mounted to freely move longitudinally of the support and arranged to be retracted to permit the device to be lowered 70 through the tubular element without engaging an accumulation on the wall of the bore thereof, means on the mandrel for expanding said members whereby as the device moves through the bore said members remove the accumulation, and 75

means for transferring the load imposed on the members during the scraping operation to the support so as to relieve the members of such load.

10. A scraper including, an axial support having a stationary inclined portion, and a plurality of freely movable scraper members surrounding said support and having arcuate overlapping scraping faces, and provided with means co-acting with said inclined portion whereby they are 10 retracted and expanded by the inclined portion of the support when moved longitudinally thereof, said scraping members forming a continuous circumferential scraper when expanded.

11. A well scraper including, an axial support adapted to be lowered into a well pipe having an accumulation in its bore, and a plurality of radially movable scraping members having arcuate overlapping scraping faces disposed to remove 5 said accumulation when the support is moved upwardly therethrough, said scraping members being so loosely and freely mounted on said support as to be readily moved radially inward by said accumulation to reduce the diameter of the 10 scraper when the support is moved downwardly therethrough.

HERBERT C. OTIS.
